Primary Examiner — Ruth McInroy(74) *Attorney, Agent, or Firm* — Faegre Baker Daniels LLP(57) **CLAIM**

We claim the ornamental design for a pool cleaner, as shown and described.

DESCRIPTION

FIG. 1 is a perspective view of a pool cleaner showing our new design;

FIG. 2 is an enlarged view of the claimed portion in FIG. 1;

FIG. 3 is a left side elevational view thereof;

FIG. 4 is a front elevational view thereof;

FIG. 5 is a right side elevational view thereof;

FIG. 6 is a rear elevational view thereof;

FIG. 7 is a top plan view thereof; and,

FIG. 8 is a bottom plan view thereof.

The broken lines in FIGS. 1-8 are for illustrative purposes only and form no part of the claimed design.
